[57] CLAIM

The ornamental design for an eye makeup applicator, substantially as shown and described.

DESCRIPTION

FIG. 1 is a perspective view of an eye makeup applicator showing our new design.

FIG. 2 is a top plan view thereof.

FIG. 3 is a side elevational view thereof.

FIG. 4 is a bottom plan view thereof.

FIG. 5 is an end elevational view of one end thereof.

FIG. 6 is an end elevational view of the other end thereof.

The characteristic feature of the design resides in the shape of the applicator head.
